Primary Examiner—James M. Gandy*Attorney, Agent, or Firm*—Leydig, Voit & Mayer**[57] CLAIM**

The ornamental design for an automobile body, as shown and described.

DESCRIPTION

FIG. 1 is a left side elevational view of an automobile body showing my new design;

FIG. 2 is a front elevational view;

FIG. 3 is a top plan view;

FIG. 4 is a rear elevational view; and,

FIG. 5 is a right side elevational view.

The broken line showing of the tires in FIGS. 1, 2, 4 and 5 of the drawing is for illustrative purposes only and forms no part of the claimed design.

FIG. 2

FIG. 4

FIG. 1

FIG. 3

FIG. 5
